UNITED STATES PATENT OFFICE.

WILLIAM R. KINNEAR, OF NEW YORK, N. Y.

PROCESS OF SEPARATING ADHERING METAL SHEETS.

1,126,482.

Specification of Letters Patent. Patented Jan. 26, 1915.

Application filed April 29, 1914. Serial No. 835,117.

To all whom it may concern:

Be it known that I, WILLIAM R. KINNEAR, a citizen of the United States, formerly a resident of New Castle, Pennsylvania, and now a resident of the city, county, and State of New York, have invented certain new and useful Improvements Relating to the Process of Separating Adhering Metal Sheets.

In the formation of what is known in the art as a "hot pack," the separate or individual sheets comprising the pack stick or adhere to each other during the operation of forming the pack, so that heretofore, it has been difficult to separate the individual sheets from each other.

One of the objects of my invention is to so manipulate the hot pack that the adhesion between the individual sheets throughout their entire area is broken or destroyed, so that the individual sheets are quickly and efficiently separated one from the other with small cost.

Other objects will appear from the hereinafter description.

The invention in its broadest aspect consists in so manipulating the hot pack that each individual sheet of the pack throughout its entire area, will have an independent surface movement or rubbing action backward and forward with respect to an adjacent sheet, thus destroying the adhesion between the individual sheets.

More particularly the invention consists first in corrugating or shaping the pack throughout its entire area into a sinuous contour and then progressively and repeatedly reversing the position of the contours and changing the crests and the depressions of the corrugations or contours.

Still more particularly the invention consists first in corrugating or shaping the pack throughout its entire area into a sinuous contour and then progressively and repeatedly reversing the position of the contours and progressively changing the crests or depressions of the corrugations or contours by causing a relative movement between the corrugated hot pack and a sinuous or tortuous passage through which the pack extends.

The invention will be more fully understood from the hereinafter description.

Any suitable apparatus may be employed for carrying out the invention, but I will now describe a machine which I have found to be particularly useful for this purpose.

The machine is illustrated in the accompanying drawings forming a part of this specification, in which:

Figure 1 is a diagrammatic plan view of the lower portion of the machine showing the corrugating dies at the middle of the machine and take-away rolls or dies at the back of the machine. Fig. 2 is a similar view to that of Fig. 1 with the corrugating rolls or dies drawn out to the end of the machine. Fig. 3 is a cross sectional view of the machine, certain parts thereof being shown in elevation. Fig. 4 is a sectional view of part of the machine shown in Fig. 3 taken on line 4 of Fig. 3. Fig. 5 is an enlarged sectional view showing one position of the corrugating rolls and the hot pack between the same. Fig. 6 is a similar view showing another relative position of the corrugating dies and the hot pack. Fig. 7 shows still another relative position. Fig. 8 is a cross sectional view of the carriages carrying the corrugating rolls or forming dies assembled at the middle of the machine, or in their initial position, the upper dies shown raised and the hot pack in position between the dies. Fig. 9 is a similar view to that of Fig. 8 with the upper dies lowered and the hot pack corrugated or formed into a sinuous shape between the dies. Fig. 10 is a similar view to that of Fig. 9 with the upper dies slightly raised from the position shown in Fig. 9. Fig. 11 is a similar view to that of Fig. 10, showing one set of dies—those on the left—slightly removed from the dies on the right. Fig. 12 shows the dies on the left moved still farther to the left and the dies on the right moved farther to the right from the position shown in Fig. 11. Fig. 13 is a view showing both sets of dies still farther separated and moving to the right and left respectively.

Referring to the drawings, in which the same reference character indicates the same part in the several views: The part marked 20 represents the bed plate of the machine and 40 the upper head thereof, the latter being movable vertically toward and from the bed plate by suitable means, not shown but well known in the art.

Formed on the bed plate are channels or guideways 21 and 22, into which extend the flanges or front and rear edges 23 and 24, respectively, of a series of lower frames or carriages 25, 26, 27 and 28. The lower part of the movable head facing the bed plate is

provided with channels or guideways 41 and 42, into which extend the flanges or front and rear edges 43 and 44 respectively, of a series of upper frames or carriages 45, 46, 47 and 48, and by which the said carriages are suspended in an inverted position on the head. The lower carriages may be and preferably are provided with rollers or wide faced wheels 29, 29^a, 30 and 30^a, and the upper carriages with similar wheels 49, and 50. These wheels take up the thrust on the carriages and permit the same to move more freely over the bed plate and across the face of the head when the hot pack is being operated on by the dies in the manner hereinafter described.

Journalled in the lower carriages are rolls 31, 31^a, 32 and 32^a and in the upper carriages are similar rolls 51, 51^a, 52 and 52^a, which 20 intermesh with each other and act as dies to corrugate or form the hot pack into a sinuous shape. The surfaces of the dies form walls of a tortuous passage and the hot pack and said walls or passage have a 25 relative movement after the pack has been corrugated.

Journalled in suitable bearings in the lower carriages intermediate the rolls or dies 31, 31^a, 32 and 32^a are sets of rollers 33, 30 and journalled in the upper carriages in similar supports and intermediate the ends of the rolls or dies 51, 51^a, 52 and 52^a, are rollers 53. The rollers 33 and 53 are arranged in pairs and straddle the dies 31, 31^a, 32, 32^a, 35, 51, 51^a, 52 and 52^a, and act as bearing rollers for said dies and prevent the dies from springing between their ends when pressure is applied to the hot pack in corrugating and treating the same.

40 Any suitable number of carriages may be used but I have shown four upper and four lower carriages and have arranged them in pairs. Each lower pair is connected by bolts 61 and 62 and each upper pair has bolts 81 and 82 which pass respectively loosely through openings 63, 65 and 66 and 83, 84, 85 and 86 in the adjacent ends of the respective carriages forming each pair. The bolts are headed at each end to permit the 45 carriages forming each pair to be separated to a limited extent. Surrounding the bolts are springs 67, 68, 87 and 88 which tend to separate the carriages of a pair. The adjacent ends of the carriages are provided 50 with recesses 69 and 89, into which the ends of the springs fit and which permit the springs to be compressed therein so that the adjacent ends of the carriages may be caused to abut or be brought close together. 55 The carriages are so constructed and the rolls or dies are so mounted with respect to each other that when the head is lowered the dies 51, 51^a, 52 and 52^a will be moved between the lower dies 31, 31^a, 32 and 32^a, 60 with the centers of the dies on a straight

line and with sufficient clearance between the adjacent faces of the dies to form a space between which the hot pack is clamped and corrugated or formed into a sinuous contour, as will more clearly appear from Fig. 9 of the drawing.

Pivoted to the outer carriage of each pair is a link 70, 71, 90 and 91, respectively, the other ends of which are connected to any suitable source of power, not shown, and by 75 which each pair of carriages is moved backward and forward or upward and away from each other over the bed plate and across the face of the head of the machine.

Secured to the bed plate in the path of movement of the wheels 29^a are cam plates or bridges 75, and in the path of the wheels 30^a are cam plates or bridges 76. These cams or bridges are so located that the wheels 29^a and 30^a will ride over them during certain movements of the carriages and will raise the carriages 26 and 27 to cause the dies 31^a and 32^a to grip the hot pack against the dies 51^a and 52^a, the relative width of the guideways 21 and 22 and the thickness of the flanges 23 and 24 being such that the said carriages 26 and 27 may have a limited vertical movement for this purpose.

Mounted at the rear of the machine and adjacent to the carriages are a series of take-away rolls 100 and 101, through which the pack is carried after being operated upon by the dies in the machine as hereinabove described.

95 The operation of the machine for carrying out my process, will now be described: With all of the carriages at the center of the machine and with the inner ends of the inner carriages abutting or in close contact as shown in Figs. 1, 8, 9 and 10, and with the head 40 raised and the upper dies raised above the lower dies, as shown in Figs. 3 and 8, a hot pack A consisting of a plurality of adhering sheets a is placed between the 100 dies and carried by the upper and lower carriages respectively as shown in Fig. 8. The head of the machine is then lowered or forced down whereupon the upper dies are moved between the lower dies and the hot 105 pack is forced between the adjacent surfaces of the upper and lower dies respectively and the hot pack is corrugated or bent into a sinuous contour form throughout its entire length as shown in Fig. 9. The head 40 is 110 now slightly raised when the dies carried by the said head recede slightly and the grip upon the hot pack will be loosened, but the pack will still be held in a sinuous contour 115 as shown in Fig. 10. As soon as this operation takes place, the carriages 25 and 45 for example, are drawn to the left by the links 70 and 90 whereupon these two carriages are 120 separated from the adjacent carriages 26 and 46 and as the strain comes upon the 125 130

bolts 61 and 81 connecting the carriages 25 and 45 with the carriages 26 and 46 respectively, the said carriages 26 and 46 are pulled to the left causing the rollers carried thereby to grip the pack against the dies 51^a adjacent thereto and carried by the carriage 46. As soon as this gripping action takes place the carriages to the right of the machine are pulled to the right by the links 71 and 91, the first movement of these carriages will cause the dies carried thereby to slip over the right hand portion of the pack for a short distance and until the wheels 30^a ride upon the cam plates or bridges 75, whereupon the dies 32^a force or grip the pack against the dies 52^a carried by the upper carriage 47. By the time this gripping action takes place, the wheels 29^a have moved off of the cam plates 75 as shown in Fig. 12 and the dies 31^a carried by the carriage 26 ungrasp the pack and the dies to the left continue to move to the left and wipe over or move over that portion of the surface of the pack to the left. During this operation the dies to the right are moving to the right and as soon as the wheels 30^a move off of the cam surface 76, the dies 32^a ungrasp the pack and the dies carried by the carriages to the right of the machine move or wipe over the pack.

As the dies to the right and left recede from each other, they straighten out the pack between the inner carriages and tend to flatten or remove the corrugations or sinuous contours as more clearly shown in Figs. 12 and 13.

Wiping the dies over the pack after it has been corrugated, causes the pack to move through a sinuous path formed by the walls of the dies which progressively change the positions of the crests and depressions of the corrugations longitudinally of the pack and thus repeatedly and successively bend the pack or form the corrugations alternately in opposite directions, whereby each individual sheet of the pack is caused to continuously move or creep backward and forward upon the adjacent sheet, thereby destroying the adhesion between the adjacent surfaces of the sheet throughout the entire extent of the pack.

In Figs. 5, 6 and 7, I have illustrated diagrammatically on an enlarged scale, the operation of the dies on the hot pack and the relative movement between the same. Assuming that the dies are moving to the right and are wiping over the pack with the crests of the corrugations in Fig. 5 at c¹, c² and c³, and the depressions at d¹, d² and d³, when the dies have moved to the

position shown in Fig. 6, that part of the pack which was at c¹ in Fig. 5, will have moved to the position shown in Fig. 6, and when the dies have moved to the position shown in Fig. 7 this part of the pack will be at c² as shown in Fig. 7 and the other crests and depressions will be changing their positions relative to the rolls accordingly, and as the dies wipe to the right, that part of the pack which was at the top of the dies and formed crests of the corrugations, will be transferred to the bottom of the dies and any particular point or area on the pack will be gradually and continuously moving in the direction of the travel of the dies. The continued movement of the dies, it will be seen, thus progressively and continuously changes the position of the contours of the pack and tends to straighten out the pack, thereby causing the individual sheets of the pack to be continuously moving or creeping one over the other throughout their entire areas, with the result that the adhesion between the individual sheets of the pack is broken or destroyed, completely separating the individual sheets one from the other throughout their entire surfaces or areas. After the pack has been operated on as thus described and the adhesion between the individual sheets broken or destroyed, the upper dies are then raised to release the pack, whereupon the pack is passed transversely through the machine to the take-away rolls 101, which flatten or straighten out the piled up separated sheets forming the pack.

Having now described my invention, what I claim as new and desire to secure by Letters Patent is:

1. The process of destroying adhesion between metal sheets forming a hot pack, which consists in corrugating the pack throughout its entire surface, then changing the positions of the corrugations by advancing the positions of the crests and depressions of the corrugations along the longitudinal direction of the pack.

2. The process of destroying adhesion between metal sheets forming a hot pack, which consists in corrugating or compressing the pack into a sinuous form throughout its entire surface, then changing the positions of the corrugations by gradually advancing the positions of the crests and depressions of the corrugations or sinuosity along the longitudinal direction of the pack while the pack is held normally in a fixed relative position.

3. The process of destroying adhesion between metal sheets forming a hot pack, which consists in compressing the sheets to form corrugations therein throughout their entire extent, then changing the positions of the corrugations by gradually changing the positions of the crests and depressions of the corrugations along the longitudinal di-

- rection of the pack, and straightening or removing the corrugations by pulling the pack from the middle portion toward its ends.
5. 4. The process of destroying adhesion between metal sheets forming a hot pack, which consists first in corrugating or shaping the pack throughout its entire surface into a sinuous contour and then causing a 10 relative movement between the corrugated hot pack and the sinuous or tortuous passage through which the pack extends, thereby progressively and repeatedly reversing the positions of the contours by advancing the 15 crests and depressions thereof along the longitudinal direction of the pack.
5. The process of destroying adhesion between sheets constituting a hot pack, which consists in causing the individual sheets of 20 the pack to be moved simultaneously relatively one to the other throughout their entire surface.
6. The process of destroying adhesion between sheets constituting a hot pack, which 25 consists in causing the individual sheets to move with respect to one another throughout their entire surface while the pack as a whole remains in a relatively fixed position.
7. The process of destroying adhesion be- 30 tween metal sheets constituting a hot pack which consists in corrugating the pack and then continuously and progressively reversing the corrugations throughout the entire surface of the pack.
- 35 8. The process of destroying adhesion between metal sheets constituting a hot pack, which consists in corrugating or compressing the pack into a sinuous form, then continuously reversing the corrugations and 40 simultaneously straightening or removing the corrugations.
9. The process of destroying adhesion be- 45 tween metal sheets forming a hot pack, which consists in corrugating the adhering sheets and then when the pack is in a relative fixed position causing the corrugations to be changed simultaneously from the middle portion thereof to the outer ends thereof.
- 50 10. The process of destroying adhesion between metal sheets forming a hot pack, which consists in so manipulating the pack that each individual sheet of the pack throughout its entire area will have an in- 55 dependent simultaneous surface movement or rubbing action backward and forward with respect to an adjacent sheet.
11. The process of destroying adhesion be- 60 tween metal sheets, which consists in caus- ing the sheets to move relatively one to another by pressing alternately in opposite directions while one end of each sheet is caused to move in opposite direction to its other end.
12. The process of destroying adhesion be- 65 tween metal sheets, which consists in causing the sheets to move relatively one to another alternately in opposite directions by pressing and in simultaneously maintaining tension on the portion being treated, while one 70 end of each sheet is caused to move in opposite direction to its other end.
13. The process of destroying adhesion be- 75 tween metal sheets, which consists in causing the adhering sheets to be treated first to be corrugated and then to move through a circuitous path whereby they are flexed or curved alternately in opposite directions and the individual sheets repeatedly caused to move longitudinally relatively one to another, while one end of each sheet is caused to move in opposite direction to its other 80 end.
14. The process of destroying adhesion be- 85 tween metal sheets, which consists in press- ing the sheets to be treated and then causing them to occupy successively different portions of a circuitous path whereby they are caused to bend or curve alternately in opposite directions while under tension and with 90 one end of each sheet moving in opposite direction to its other end.
15. The process of destroying adhesion in 95 a pack of metal sheets, which consists in pressing the sheets to be treated between in- termeshing corrugated surfaces forming a circuitous path and then causing a relative movement between said surfaces of the circuitous path, thereby alternately concaving and convexing the pack whereby the sheets 100 are made to creep or move one upon another while one end of each sheet is caused to move in opposite direction to its other end.
16. The process of destroying adhesion be- 105 tween metal sheets which consists in press- ing the pack of sheets to be treated between intermeshing corrugated surfaces causing a relative movement between said surfaces and the pack while one end of each sheet is caused to move in opposite direction to its 110 other end, and thereafter passing the portion thus treated through plain rolls.
17. The process of destroying adhesion be- 115 tween metal sheets, which consists in forcibly pressing the pack of sheets to be treated between intermeshing corrugated surfaces causing a relative movement between said corrugated surfaces and the pack, and there- 120 after passing the sheets thus treated through plain rolls in a direction parallel to the length of the corrugations thus developed in the sheets.
18. The process of destroying adhesion in 125 a pack of metal sheets by pressing the op- posed portions of the pack between pairs of dies, each pair having a relatively fixed cir- cuitous passage, and moving the pairs of dies in opposite directions to cause a relative

movement between the engaged portions of the pack and said circuitous passage.

19. The process of destroying adhesion in a pack of sheets, consisting of treating successively different areas of the outer portion of the pack by pressing said portions between members having registering corrugated surfaces and then developing relative movement between the pack and said members to produce the effect of drawing the pack endwise through a circuitous path which imparts repeated and alternating bending of the pack while one end of each sheet is caused to move in an opposite direction to its other end.

20. The process of destroying adhesion in a pack of sheets, which consists in treating different areas of the pack by pressing the pack between members having registering corrugated surfaces and then developing relative movement between the pack and said members to produce the effect of drawing the pack edgewise through a circuitous path which imparts repeated and alternating bending of the pack, said areas being

treated in the order of their nearness to the outside of the pack.

21. The process of destroying adhesion in a pack of metal sheets, consisting in treating successively different areas of the pack by pressing the pack between members having registering corrugated surfaces and then developing relative movement between the pack and said members to produce the effect of drawing the pack edgewise through a circuitous path which imparts repeated and alternating bending of the pack, said areas being treated in the order of their nearness to the outside of the pack, said pack being treated simultaneously on opposite sides of an intermediate transverse line toward the ends.

In witness whereof I have hereunto set my hand at the borough of Manhattan, city and State of New York, this thirteenth day of April, 1914.

WILLIAM R. KINNEAR.
